SINGLE REVOLUTION DRIVE CONTROL FOR
ROTARY PRINTING PRESSESWilliam Ward Davidson, Evanston, Ill., assignor,
by mesne assignments, to Davidson Corpora-
tion, a corporation of Illinois

Application October 1, 1947, Serial No. 777,245

5 Claims. (Cl. 101—245)

1

My present invention relates to an improvement in printing presses.

It is an object of my invention to provide a printing press adapted to be manually or motor driven through successive single cycles of operation under the control of the operator and in which sheets to be printed may be hand fed by the operator.

In my prior Patent No. 2,387,750 dated October 30, 1945, there is disclosed a printing press which may be readily adapted for either offset or direct printing, and which press comprises a pair of printing cylinders in which one cylinder is of twice the diameter of the other cylinder. The cylinder of large diameter, when the press is to be used for offset printing, includes a cylindrical plate segment for carrying a lithographic printing plate made of paper or metal, and a cylindrical platen or impression segment providing an impression surface, and in which the cylinder of small diameter carries a blanket made of rubber or like material. The two cylinders are rotated conjointly and in each complete revolution of the large plate and platen cylinder the blanket cylinder is rotated twice. Suitable dampening and inking means are arranged with respect of the large plate and platen cylinder so that in substantially one half revolution thereof of the plate carried by the plate segment is first dampened and then inked. In the succeeding half revolution of the large plate and platen cylinder and the complete revolution of the blanket cylinder i. e. when the plate is in engagement with the blanket the inked image of the plate is transferred to the blanket of the blanket cylinder. During the next succeeding half revolution of the large plate and platen cylinder when the plate is again being dampened and inked a sheet is adapted to be fed between the printing couple formed by the platen or impression segment and blanket so that the inked image on the blanket is transferred to the sheet. Thereafter in one half revolution of the plate and platen cylinder and one complete revolution of the blanket cylinder the plate carried by the plate and blanket cylinder is being dampened and inked while a sheet fed between the platen or impression segment and blanket cylinder is being printed. In the following half revolution of the large plate and platen cylinder and the following complete revolution of the blanket cylinder the inked image from the inked plate is being transferred to the blanket of the blanket cylinder for the printing of a succeeding sheet. The press may readily be converted into a direct printing press by sub-

2

stituting a direct letter printing plate carrying segment for the platen or impression segment of the large diameter cylinder. The plate segment is removed from the large cylinder and a hard platen surface is substituted for the blanket or an impression cylinder may be substituted for the small diameter blanket cylinder. The dampening mechanism used when the machine is set up for offset printing may be arranged so that it may be disposed in an inoperative position or removed from the machine when it is thus converted for direct printing. In the machine modified in the manner noted the direct letter plate carried by the large diameter cylinder is adapted to be inked by the inking means with a sheet to be printed being adapted to be fed between the inked plate and the impression surface of the small surface cylinder to effect printing of the sheet. In the machine of my above patent several power driven instrumentalities are provided, such as a power driven sheet feeding mechanism for driving a sheet to be printed into the printing couple, and the press further includes other instrumentalities such as a detector means for detecting if a sheet which is to be printed is present at the time it is to be fed between the cylinders for printing, and latch means operable for separating the printing cylinders if a sheet to be printed is not present at the proper time in the cycle of operation of the press to prevent undue transfer of ink from the plate to the blanket all to the end of providing a press of the character indicated suitable for the rapid production of a large number of copies from a single plate.

In many instances it is desirable to produce only a few copies from each of several plates and while that may be done with the press of my above patent the power driven and other instrumentalities of the character above noted embodied in that press are not needed for such purposes and the cost of the press for such use therefore is a disadvantage from the economic standpoint.

It is a further object of my invention to provide a press embodying the aforementioned relation of printing cylinders which may be manually or motor driven through a single cycle, i. e., one complete revolution of the large diameter cylinder and two revolutions of the small diameter cylinder and in a manner in which sheets to be printed may be hand fed to the press while the cylinders are in stationary position.

In the aforementioned relation of printing cylinders, I propose to embody gripper means rotatable with the large cylinder for gripping the

55

leading edge of a sheet to be printed for drawing the sheet through the printing couple formed by the cylinders. The gripper means preferably is of a character which is normally spring biased to closed position and it is a preferred feature of my present invention to arrange such gripper means so that it is disposed in open position at the beginning of a printing cycle. A further preferred feature of my invention resides in the provision of stop means for positioning the plate and platen cylinder and blanket cylinder in a predetermined stationary relation with respect of each other with the stop means being adapted to effect opening of the gripper means so that a sheet may be hand fed thereinto. After the sheet to be printed has been positioned in the open gripper means the gripper means is caused to be closed upon the leading edge of the sheet by release of the stop means and after which the pair of cylinders may be manually or motor driven so that the gripper means draws the sheet between the printing couple formed by cylinders. In the press when arranged for offset printing the plate carried by the plate segment of the plate and platen cylinder is dampened and then inked by suitable dampening and inking means of the press followed by the transfer of the inked image of the plate to the blanket means after which the stop means is operative to effect stopping of the cylinders in their aforesaid predetermined relation with the gripper means in open position for receiving the leading edge of the next sheet to be printed. With the press arranged for direct printing the dampening means is of course eliminated and the cylinders are disposed in their stationary predetermined relation after inking of the direct letter plate.

Suitable ejector cam means is provided to effect opening of the gripper means after a sheet has been drawn through the printing couple. A further important feature of a preferred embodiment of the press of my invention resides in the arrangement of the large diameter plate and platen cylinder with the dampening and inking means for the press so that when the cylinders are in their stationary predetermined position the impression segment, when the press is arranged for offset printing, is disposed adjacent the dampening and inking means, and in which the impression segment includes any convenient form of means such as form roll cam means for biasing the dampening and inking means out of engagement therewith. In the press arranged for direct printing the inking means is arranged so that it is out of contact with the direct letter plate in the predetermined stationary position of the cylinders. In either form of the press the aforesaid arrangement is of importance in that the lithographic plate or direct letter plate will not at any time be in stationary engagement with the inking means so that streaking which might occur if such condition did exist is avoided.

In the press of my above patent the cylinders are arranged so that the large diameter cylinder is disposed above the small diameter cylinder with the gripper means for conveying the sheets through the printing couple being carried by chain means rotatable with the small cylinder. In the machine of my present invention it is preferred to arrange the cylinders so that the small cylinder is disposed above the large cylinder and to mount the sheet gripping means for rotation with the large cylinder. Such arrangement of the cylinders provides the easy feeding of a sheet to be printed in the open gripper means in the sta-

tionary position of the cylinders, and further provides for the convenient actuation of the gripper means and of the arrangement of the inking or dampening and inking means for either a direct printing press or offset press.

It is a further object of my invention to provide a convenient hand operable means for driving the press through a single cycle of operation in the manner above noted.

A further object of my invention is to provide a press of the character above described including motor means for successively driving the same through successive cycles of operation under the control of manually actuated trip means.

A still further object is to provide a press which may be manually or motor driven through successive single cycles of operation at the option of the operator of the press.

It will be understood that while I shall describe my invention primarily in connection with the press arranged for offset printing that, as above noted, the press may be readily converted for direct printing with the press when so modified also being operable for successive single cycles of operation and in which the sheets to be printed may be hand fed into stationary open gripper means at the starting of a cycle of a printing operation of the press.

The above and other objects, advantages and features of my invention will appear from the following detail description of certain preferred embodiments of my invention.

Now in order to acquaint those skilled in the art with the manner of constructing and utilizing printing presses in accordance with my present invention, I shall describe in connection with the accompanying drawings certain preferred embodiments of my invention.

In the drawings:

Figure 1 is a side view, largely diagrammatic, of a manually operable printing press embodying my present invention in which the major portion of the side wall of the press toward which it is viewed in the drawing being broken away to more clearly illustrate the relation of the several parts of the press;

Figure 2 is a partial plan and sectional view taken substantially along the line 2—2 of Figure 1 looking in the direction indicated by the arrows and showing the arrangement of the stop means, the gripper means, and the cam means between the stop and gripper means of the press;

Figure 3 is a side elevational view of another embodiment of a press constructed in accordance with my invention in which the press is adapted to be manually or power driven;

Figure 4 is an enlarged side elevational view of the upper portion of the press of Figure 3 and showing the parts of the press in position at which a sheet to be printed is adapted to be hand fed into the press;

Figure 5 is a side elevational view similar to Figure 4 showing the position of the parts of the press after the stop means thereof has been released at the beginning of a cycle of operation of the press;

Figure 6 is an end view of the upper portion of the press taken substantially along the line 6—6 of Figure 4 looking in the direction indicated by the arrows and with certain parts being broken away and shown in section;

Figure 7 is an end view of the upper portion of the press taken substantially along the line 7—7 of Figure 5 looking in the direction indicated by the arrows with certain parts being broken away;

Figure 8 is a detail sectional view taken substantially on line 8-8 of Figure 4 showing a latch mechanism providing for controlling engagement of a clutch for the drive means of the press in latched position in which the clutch is disengaged;

Figure 9 is a detail view of the latch mechanism of Figure 8 taken substantially along the line 9-9 of the latter figure looking in the direction indicated by the arrows;

Figure 10 is a detail sectional view similar to Figure 8 showing the latch mechanism released with the view being taken substantially along line 10-10 of Figure 5 looking in the direction indicated by the arrows;

Figure 11 is a detail view similar to Figure 9 showing the latch mechanism released with the view being taken substantially along line 11-11 of Figure 10 looking in the direction indicated by the arrows;

Figure 12 is a detail vertical sectional view taken substantially along line 12-12 of Figure 7 looking in the direction indicated by the arrows and illustrating the manner in which a clutch control rod carries a clutch fork for disengaging the clutch of the drive mechanism for the press;

Figure 13 is a detail sectional view somewhat along the lines of Figure 8 showing cam means associated with the clutch of the press in which the clutch is in disengaged position;

Figure 14 is a view similar to Figure 13 showing the position of the cam means associated with the clutch of the press in which the clutch is in engaged position;

Figure 15 is a partial side elevational view of a portion of the plate and platen cylinder showing in full lines an actuating pin carried thereby and a lever forming part of a latch mechanism for retaining manually operable trip means for the press in tripped position with the lever and actuating pin being shown in dotted lines in the position for releasing such latch mechanism; and

Figure 16 is an enlarged partial side elevational view of the releasable stop means for the press of Figure 3.

Referring now to Figures 1 and 2 of the drawings I have shown my invention embodied in a press adapted to be manually driven and comprising a pair of spaced side walls 6 and 7 with the side wall 6 as viewed in Figure 1 being largely broken away for purposes of illustrating the relation of the several parts of the press. The side wall 6 is of the same form as side wall 7 illustrated in full outline in Figure 1 and between the pair of spaced side walls 6 and 7 a plate and platen cylinder 8 of known construction is rotatably mounted upon a transversely extending shaft 9 supported for rotation in suitable bearings at its opposite ends carried by the side walls 6 and 7. A blanket cylinder 11 is carried by a transversely extending shaft 12 mounted at its opposite ends in the side walls of the frame of the press and in position above the plate and platen cylinder 8. The shaft 12 as shown comprises eccentric trunnion end portions 14 which as is well known in this art provide for adjustment of the blanket cylinder 11 with respect of the plate and platen cylinder 8 for adjusting the pressure of the engagement of a transfer blanket 15 made of rubber or the like, covering substantially the entire periphery of the blanket cylinder 11, with the impression or platen surface of an impression segment of cylinder 8 shown schematically at 16, and which impression segment 16 forms substantially one half of the plate

and platen cylinder 8. A plate segment 17 for carrying a lithographic printing plate, diagrammatically illustrated at 18, together with the impression segment 16 form the plate and platen cylinder 8 in a manner well known in this art and shown, for example, in greater detail in my above patent. In that the plate and platen cylinder 8 of the type above described is well known in the art as is the blanket cylinder 11 and the blanket 15 carried thereby it is believed a further detail description of these members is not essential for understanding of my present invention. The construction of these two cylinders may vary widely for use in my present invention with the only essential of such cylinders being that they provide a printing couple of character as will hereafter appear. As previously referred to the plate and platen cylinder 8 is of twice the diameter of the blanket cylinder 11 so that for each complete revolution of the plate and platen cylinder 8 the blanket cylinder is rotated twice. The plate segment of cylinder 8 together with the lithographic plate carried thereby and the blanket cylinder 11 and blanket 15 carried thereby form a printing couple in a known manner. In the rotation of the plate and platen cylinder 8 in a counterclockwise direction as viewed in Figure 1, the plate 18 is adapted to be damped by a dampening means of known construction, indicated generally at 20, and then inked by an inking means of known construction, shown generally at 22, and which upon rotation of the printing plate with the blanket cylinder 11 transfers the inked image from the plate 18 to the blanket 15 carried by blanket cylinder 11. Upon feeding of a sheet between the printing couple formed by the blanket 15 of the blanket cylinder 11 and the impression surface 16 of the impression segment the inked image on the blanket is transferred to the sheet. Thus, in each full revolution of the plate and platen cylinder 8 and two full revolutions of the blanket cylinder 11 the plate carried by the plate segment is caused to be damped and inked for transferring an inked image to the blanket 15 of the blanket cylinder 11, and the inked image transferred from the plate to the blanket of the blanket cylinder is transferred to a sheet fed between the printing couple formed by the blanket 15 and the impression segment 16. For purposes of manually driving the press of Figure 1 I provide a crank 23 which is suitably secured to the shaft 9 as by the pin 24 so that upon rotation of the crank the plate and platen cylinder 8 is rotated. The plate and platen cylinder 8 carries an end gear member which has meshing engagement with an end gear secured to the blanket cylinder 11 in a known conventional manner so that upon rotation of the plate and platen cylinder the blanket cylinder is adapted to be conjointly rotated therewith.

The crank 23 at its outer end carries handle means 21 adapted to be grasped for rotating the crank and comprising a cylindrical sleeve 25 closed at its outer end by a cap member 26 forming, in part, a releasable stop member the purpose of which is described below. The sleeve 25 is adapted to have sliding movement on a shaft portion 27 formed integral of the crank arm 28 of the crank 23. The releasable stop member further comprises a plunger 29 which is secured at one end thereof in a bore 30 in the cap member 26 as by means of a cross pin 32. A coil spring 33 is contained within a bore 35 of the shaft extension 27 of the crank and is confined between

a shoulder 36 at the inner end of the plunger 29 and the opposite end of the bore 35 with the spring 33 normally tending to bias the plunger 29 inwardly toward the side wall 6 of the frame of the press in position so that the tapered outer end portion 38 thereof is normally disposed in a position to engage a fixed stop member 39 preferably formed integral with the side wall 6 to prevent rotation of the plate and platen cylinder 8 and the blanket cylinder 11 when these cylinders are in the position shown with respect to each other. The releasable stop member is rotatable with the plate and platen cylinder and is carried by the crank in advance of the leading edge of the impression segment thereof. The sleeve 25 is adapted to be grasped in one hand and moved axially to the left as viewed in Figure 2 against the force of the spring 33 for drawing the tapered end 38 from engagement with the fixed stop member 39. The releasable stop member when thus released from the fixed stop member 39 permits rotation of the crank in a counterclockwise direction as viewed in Figure 1 to rotate the plate and platen cylinder and the blanket cylinder conjointly for effecting and printing of a sheet fed between the impression segment 16 and the blanket 15 of the blanket cylinder 11 in the manner already referred to. The plate and platen cylinder 8 carries a normally closed gripper means indicated generally at 40 in advance of the leading edge of the impression segment 16, and which gripper means as more clearly shown in Figure 2 comprises a shaft 42 having a plurality of gripper fingers 43, only one of which is shown in the drawing, fixed thereto and between which gripper fingers and an anvil 44 of the impression segment 16 the leading edge of a sheet to be printed is adapted to be grasped for drawing the sheet through the printing couple. A coil spring 45 is disposed about the shaft 42 and one end thereof is fixed as at 46 to the plate and platen cylinder 8 with the opposite end of the spring being secured in a collar 47 fixed to the shaft 42 as by a set screw 48. The spring 45 is preloaded so that it normally tends to bias the shaft 42 in a direction to urge the gripper fingers 43 into engagement with the anvil portion 44 at the leading edge of the impression segment 16. A crank arm 50 fixed at one end to one end of the shaft 42 carries at its outer or other end a cam follower or roller 52 which is adapted to have engagement with the cam surface of a crank arm 55 forming in part a cam means indicated generally at 56.

The crank arm 55 is keyed to one end of a shaft 57 extending through the side wall 6 of the frame of the press with the shaft 57 at its other end having a crank arm 58 fixed thereto. The crank arm 58 is normally disposed in a position to be engaged by the outer end of the plunger 29 of the handle means 21 of the crank means 23. A coil spring 60 is fixed at one end to the crank arm 55 and at its other end to a pin 62 fixed in the adjacent side wall 6 normally tends to rotate the crank arms 58 and 59 about shaft 57 in a clockwise direction as viewed in Figure 1 of the drawings. With the parts disposed in the latter position it will be observed that in the normal inward position of the plunger 29 that the end 38 thereof is in engagement with the fixed stop member 39 of the press, and is also in engagement with the crank arm 58 biasing the crank arm 55 against the force of spring 60 into engagement with the cam follower 52 of the crank arm 50 of the gripper means 40. The crank arm 50 in the latter posi-

tion has rotated shaft 42 against the force of spring means 45 to a position in which the gripper fingers 43 are positioned away from the anvil portion 44. Thus, with the parts of the press in the position shown in Figures 1 and 2 a sheet is adapted to be hand fed into the open gripper means 40 from a suitable feed table 63 to dispose the leading edge of the sheet into the opened gripper means. After the sheet has been disposed in the opened gripper means the sleeve 25 of the handle means 21 may be moved axially to the left as viewed in Figure 2 to withdraw first the end 38 of the plunger from engagement with the crank arm 58 of the cam means 56. Upon release of the crank arm 58 of the cam means 56 the spring 60 rotates the crank arms 58 and 55 in a clockwise direction as viewed in Figure 1 to a position in which the crank arm 55 engages the stop pin 64 fixed in the side wall 6 of the frame. During this movement as the crank arm 55 moves away from crank arm 50 the coil spring 45 rotates shaft 42 in a direction to close the gripper fingers 43 upon the leading edge of the sheet. Further axial movement of sleeve 25 to release plunger 29 from stop member 39 releases crank 23 for rotation in a counterclockwise direction so that the sheet gripped between the gripper fingers 43 and the anvil 44 is adapted to be drawn through the printing couple formed by the impression segment 16 and the blanket 15 of the blanket cylinder 11 to effect printing of the sheet. After the plunger 29 has been withdrawn from engagement with the crank arm 58 of the cam means 56 and the stop member 39 and the crank 23 rotated beyond the latter stop member the sleeve 25 is released for movement axially inwardly toward the side wall 6 under the influence of the spring 33 so that in the continued rotation of the crank the plunger will be disposed in its normal position to engage the stop member 39 upon completion of a single revolution of the plate and platen cylinder 8.

After a sheet has been hand fed into the open gripper means 40, the gripper means closed, and the plate and platen cylinder 8 rotated in a counterclockwise direction as viewed in Figure 1 the follower 52 of the gripper means 40 after the sheet has been drawn through the printing couple is adapted to engage a stationary ejector cam 66 suitably arranged and supported by the frame of the press to open the gripper means 40. A conventional form of sheet ejector wheel means 67 extending transversely between the side walls of the press and a conventional form of stripping means 68 are provided adjacent the ejector cam 66 to strip the print sheet and direct the same into a suitable catcher 69. After the printed sheet has been stripped the cam follower 52 leaves the cam surface of the stationary ejector cam member 66 and the gripper means returns to its normally closed position until the follower 52 at the completion of a single revolution of the plate and platen cylinder again engages the crank arm 55 of the cam means 56 which is disposed by engagement of plunger 29 with crank arm 58 in a position to open the gripper means 40. As previously referred to, the dampening means 20 and the inking means 22 per se are of conventional construction but which in a preferred form of my present invention are arranged in a novel manner with respect to the plate and platen cylinder 8. The impression segment 16 of the plate and platen cylinder 8 at each end thereof is provided with a form roll cam member 70 adapted to have engagement with an end plate member 71 at each end of

a shaft 72 carrying a dampening form roller 73. The form roller cam members 70 when in engagement with the end plate members 71 position the dampening form roller 73 out of engagement with the periphery of the impression segment 16. The dampening form roller 73 is normally spring biased by spring means 74 in a direction for engagement with the plate and platen cylinder, but, when, as noted, the plate segment is passing the dampening form roller, the cam members 70 and the end plates 71 are adapted to position the dampening form roller 73 away from and out of engagement with the periphery of the impression segment. The dampening form roller 73 has the shaft 72 thereof carried in arms 76 at the opposite ends thereof pivotally mounted in the side walls of the frame as indicated at 77 with the arms 76 each carrying an adjustable set screw 78 adapted to have engagement with lugs 79 extending inwardly of side walls 6 and 7 of the press for adjusting the pressure of engagement of the dampening roller 73 with the plate carried by the plate segment of the plate and platen cylinder 8. The inking means 22 is of the same construction as the dampening means 20 above described and the primed reference characters correspond to the reference characters used in describing the dampening means 20. The inking means 22 is positioned so that the end plates 71' thereof are adapted to have engagement with the form roll cam members 70 for maintaining the ink form roller 73' out of engagement with the periphery of the impression segment. The dampening means, as diagrammatically illustrated in Figure 1, further comprises a receptacle 82 for containing the dampening solution and a roller 83 for transferring the dampening solution from the receptacle 82 to the dampening form roller 73. The inking means 22 also comprises a receptacle 82' and a roller 83' for transferring ink to the ink form roller 73' for application by the latter roller of ink to the plate carried by the plate segment.

In the position of the parts shown in Figure 1, an inked image from the plate carried by the plate segment has in the preceding half revolution of the plate and platen cylinder been transferred to the blanket 15 of the blanket cylinder, so that after hand feeding of a sheet into the open gripper means 40 actuation of the crank means 23 in the manner described effects drawing of the sheet through the printing couple formed by the blanket cylinder and the impression segment for transferring the inked image on the blanket to the paper sheet. While a sheet is being drawn through the printing couple of the press, it will be observed that the plate carried by the plate segment is being dampened and inked by the dampening and inking means 20 and 22, respectively, and prior to completion of the single revolution of the plate and platen cylinder, the inked impression of the plate has been transferred to the blanket cylinder, so that when the parts again assume the position shown in Figure 1 upon completion of a single revolution of the plate and platen cylinder 8, the press is conditioned for effecting printing of a following sheet in the next cycle of operation of the press. The dampening and inking means are so arranged in the press so that when the cylinders are in the position shown in Figure 1 they are disposed in juxtaposition of a portion of the platen segment but with the form rollers thereof out of engagement with the periphery of the platen segment by the means above described.

Referring now to the embodiment of my invention shown in Figures 3 through 16 the parts of the press identical or substantially identical to the parts of the press already described bear the same reference numerals and these parts of the press function in the manner above noted. In the press of Figures 3 through 16 the plate and platen cylinder 8 and the blanket cylinder 11 are mounted as previously described for rotation in 10 a frame formed by the spaced side walls 6' and 7'. As shown more clearly in Figure 6 it will be seen that a gear 90 carried by the blanket cylinder shaft 12 has meshing engagement with a gear 92 fixed to the plate and platen cylinder shaft 9. 15 A drive gear 93 having meshing engagement with the gear 92 is rotatably mounted about a drive shaft 94 of driving means indicated generally at 95 in Figures 3, 6 and 7. The gear 93 is mounted on the drive shaft 94 about a bearing 96 and the drive shaft 94 extends transversely between the side walls 6' and 7' below the plate and platen cylinder 8 with the opposite ends of the shaft being suitably journaled in bearings carried by the side walls. A pulley 98 is keyed to the drive shaft 94 at the end portion thereof inwardly of side wall 7'. In Figure 3 it will be seen that the drive means 95 further comprises an electric motor 99 mounted in the base 100 for supporting the upper frame formed by side walls 6' and 7' 20 with the armature shaft of the motor carrying a worm 102 which has meshing engagement with a worm wheel 103 fixed to a shaft 104 which carries a pulley about which pulley and the pulley 98 and endless belt 105 is trained. The motor 99 25 when the press is to be power driven is continuously energized so that the drive shaft 94 is constantly rotated. A clutch collar member 106 is rotatable with the drive shaft 94 by means of a pin 107 fixed in the latter and fitting in a slot 108 in the collar member with the slot and pin connection providing for axial movement of the collar member on the drive shaft 94. A coil spring 109 is disposed about the drive shaft 94 30 and is compressed between the collar member 106 and a pair of adjusting nuts 110 having threading engagement with the threaded portion 112 of the drive shaft 94. The spring 109 normally tends to bias the clutch collar 106 toward the gear 93 to engage friction clutch disks 113 and 114 disposed, respectively, between the end face of gear 93 and the adjacent end face of clutch collar 106 35 and the other end face of drive gear 93 and the adjacent end face of pulley 98. The clutch thus formed by the collar member 106 and the friction disks 113 and 114 when engaged, clutches the drive gear 93 to drive shaft 94 and since the gear is in meshing engagement with gear 92 and the latter with gear 90 the gears 90 and 92 are caused to be rotated for conjointly rotating the pair of cylinders 8 and 11. 40

45 A clutch control rod 116 extends transversely between side walls 6' and 7' parallel with and adjacent the drive shaft 94 and has a shift fork 117 secured thereto having a yoke extending into an annular groove 118 of clutch collar member 106 for shifting the latter as viewed in Figure 7 to the left against the force of spring 109 to disengage the clutch as shown in Figure 6 to permit drive shaft 94 to rotate without rotating drive gear 93 and through the latter the gears 92 and 90. 50

55 The clutch control rod 116 extends at the opposite ends thereof through holes provided therefor in side walls 6' and 7'. A cam member 122 60 is fixed externally of side wall 6' through which

75

the adjacent end portion of the clutch control rod 116 slidably extends with the latter also freely carrying a cam member 123. The cam members are provided with interengaging cam teeth 124. A lever 126 is secured to cam member 123 for slight relative rotation with the respect to the clutch control rod 116 and is provided with an extending arm portion 127. A pair of adjustable thrust nuts 128 have threading engagement with the threaded end portion 130 of the rod 116 and retain the lever 127 and cam member 123 in position at the end of the clutch control rod 116. A coil spring 129 is secured at one end adjacent the outer end of the arm 127 of the lever 126 and at its other end about a pin 129' fixed to the side wall 6' with the spring 129 normally tending to rotate the lever 126 as viewed in Figures 3, 4 and 5 in a counterclockwise direction and which movement of the lever tends to rotate the cam member 123 away from the fixed cam member 122 through the interengaging cam teeth 124 therebetween for urging the cam member 123 and the lever 126 to the left as viewed in Figures 13 and 14 to engage lever 126 into engagement with the adjacent thrust nut 128 to shift the clutch control rod 116 to the left as viewed in Figures 6, 7, 13 and 14 to disengage the clutch. Upon movement of the lever 126 in a clockwise direction from the position shown in Figure 4 to the position shown in Figure 5 the interengaging cam teeth 124 of the cam members 122 and 123 permits axial movement of the clutch control rod 116 as will hereinafter appear as viewed in Figures 13 and 14 to effect engagement of the clutch for the drive gear 93. A manually operable trip means, operable with respect of the parts just described, is provided for effecting engagement and disengagement of the clutch for the gear 93 and will be described in detail below. For the present it will be observed that when the cam members 122 and 123 are in the position shown in Figure 13 the clutch for the drive gear 93 is disengaged and when the cam members 123 and 124 are in the position shown in Figure 14 the clutch for the drive gear 93 is engaged.

Referring now, more particularly to Figures 8 through 11, it will be further seen that the clutch control rod carries at the end portion inwardly of side wall 6' a block member 130 forming in part a latch mechanism 132 for preventing engagement of the clutch means for drive gear 93. The latch mechanism 132 comprises a latch member 133 pivoted at one end by the bolt 134 to block member 130. The latch member 133 extends through a slot 135 in side wall 6' and at its other end is provided with a notch 136 for engaging the portion of side wall 6' at the upper end of the slot to engage the latch mechanism. A leaf spring member 137 is fixed at one end to the block member 130 in any suitable manner and is tensioned so that the other end thereof engages the bottom edge of latch member 133 to bias normally the latter in a direction for engaging the notch 136 with the side wall 6' at slot 135. Referring again to Figures 13 and 14 it will be observed that when the latch mechanism 132 is engaged the clutch control rod 116 is held in position in which position the cam member 123 is biased away from the cam member 122 by the interengaging cam teeth thereof and when the latch member 133 is in disengaged position as shown in Figure 14 the cam member 123 is shifted ax-

ially inwardly toward the cam member 122 with the cam teeth 124 therebetween fully in engagement under the force of the spring 109 of the drive shaft 94 acting through the shift fork 5 117 fixed to the clutch control rod 116. The latch mechanism 132 is adapted to be disengaged as shown in Figure 14 by the manually operable trip means already referred to and which shall be presently described. The function of the lever 126 and the spring 129 therefor is for purposes of re-engaging the latch member 133 from its disengaged position, shown in Figure 14, to its engaged position, shown in Figure 13, by movement of the cam member 123 relative to the cam member 122 with the cam teeth 124 therebetween and together with the spring 129 providing for axial movement of the cam member 123 and lever 126 into engagement with the thrust nuts 128 for shifting the clutch control rod 116 to the left against the force of spring 109.

Referring now to Figures 4 through 7 and 16 it will be seen that the crank arm 23 carries a handle means 21' similar in all respects to handle means 21 already described except that the sleeve 25' thereof has a projection 140 shown most clearly in Figures 6 and 7 fixed thereto and extending inwardly of the inner end of sleeve 25' toward the side wall 6' of the press and which projection 140 when engaged by the manual trip means to be described is moved to the left as viewed in the figures last referred to provide for the release of the crank 23 for rotation in a clockwise direction of the press from the predetermined stationary position at the start of a cycle of operation. The plunger 29 of handle means 21' as before is adapted to be disposed normally in a position in which it will engage the crank arm 58 of cam means 56 for the gripper finger means 49. The inner end of plunger 29 is also adapted to have engagement with a stop means 142 shown most clearly in Figure 16 carried by the side wall 6' of the press. The stop means 142 comprises a lever 143 pivotally mounted at one end to the side wall 6' as indicated at 144. The lever 143 is spring biased to a position in which it may be engaged by the inner end of plunger 29 when the latter is disposed in its normal position by means of a coil spring 146 disposed about a rod 147 between adjusting nuts 148 threaded on the rod 147 and a stationary support 149 suitably secured to side wall 6'. The lower end of rod 147 extends through support 149 with the lower threaded end of the rod having adjusting nuts 150 threaded thereon and which nuts are normally biased into engagement with the support 149 by the biasing force of spring 146. The upper end of rod 147 has pivotal connection at 152 adjacent the other end portion of lever 143. By virtue of this construction the coil spring 146 biases rod 147 upwardly with the nuts 150 limiting the uppermost position of the end of the lever 143 opposite its end pivotally mounted at 144. When the plunger 29 is in its normal inwardly disposed position as shown in Figure 6 it is adapted to be positioned in the recess 152 in the upper edge of the lever 143 so that the releasable stop means formed by the plunger 29 and the member 143 provide for the disposal of the cylinders in the position indicated in Figure 4 at the start of a printing cycle for the press. When the plate and platen cylinder 8 is rotated and approaches the completion of a single revolution at the end of a printing cycle of the press the plunger 29 is

adapted to engage the nose portion 155 of the lever 143 for biasing the lever 143 about its pivot 144 in a counterclockwise direction as viewed in Figure 16 with such movement of the lever 143 effecting compressing of the spring 147 to provide a resilient stop for the plate and platen cylinder 8 upon completion of a single revolution thereof. The high surface 156 of the recess 152 prevents rotation of the crank 23 beyond the position shown in Figure 4. In the normal position of the plunger 29 with the cylinders in the relative position with respect to each other shown in Figure 4 the inner end portion of the plunger engages the crank arm 58 of the cam means 56 and provides for disposing the gripper fingers 42 of the gripper means 40 in open position in the manner previously described.

Referring again to Figure 3 I have shown manually operable trip means 160 effecting actuation of the press through a single cycle of operation by the motor 99. The trip means 160 as shown comprises a foot treadle 162 pivotally mounted at one end as at 163 in the lower portion of the base frame 100. A coil spring 164 is connected to a pin 165 fixed to the treadle 162 with the spring 164 at its other end being fixed to a pin 166 carried by the base frame and with the spring normally tending to dispose the treadle 162 in its uppermost position against the stop 167. A link 170 has a slot 172 at the lower end thereof within which a pin 173 fixed to the treadle extends. The link 170 at its upper end as shown most clearly in Figures 9 and 11 has connection by means of a bolt 175 to the outer end of a crank arm 176 which projects through a slot 177 in side wall 6'. The crank arm 176 is fixed to a horizontally extending shaft 178 carried by bearings 179 carried by the outer surface of the side wall 6'. The shaft 178 has a crank arm 180 secured thereto at the end thereof opposite crank arm 176 with the projecting arm 182 of the crank arm extending through an opening 183 in the side wall 6' of the frame. A link 185 is pivotally connected as at 186 at the end of arm 182 of crank arm 180 and the link 185 at its upper or other end has pivotal connection at 188 to a crank arm 190 fixed to a shaft 192 extending horizontally outwardly of the side wall 6' at the upper end thereof. The arm of the crank member 190 extends through an opening 193 providing for the aforesaid disposal of the shaft 192 with the shaft 192 being supported on the outside of side wall 6' of the frame by a pair of bearings 195 carried by the side wall. The other end of the shaft 192 carries a crank arm 198 which as shown is disposed in a position to engage the projection 140 of sleeve member 25' when the crank 23 is disposed in the position shown in Figures 4 and 6 of the drawings.

Referring again to Figure 3 it will be seen that a coil spring 200 is connected at one end to the link 170 and at its other end is disposed about a pin 202 fixed to the side wall 6' of the upper frame of the press with the spring 200 acting to bias normally the link 170 upwardly to the position shown in Figures 3 and 4. In the uppermost position of the link 170 the crank arm 176 is disposed in the position shown in Figures 4, 6 and 8 with shaft 178 and the crank arm 180 disposing the link 185 and crank arms 190 and 198 in the position shown in Figure 6 of the drawings. When the treadle 162 is depressed the link 170 is drawn downwardly by the engagement of the pin 173 in the end of slot 172 against the force of spring 200 and

through the connection of the upper end of the link 170 by means of the bolt 175 with the crank arm 176 effects rotation of the shaft 178 and the crank arm 182 to draw downwardly the link 185. Downward movement of the link 185 through crank arm 190 rotates shaft 192 and crank arm 198 to the position of the latter illustrated in Figures 5 and 7 of the drawings in which the crank arm 198 engages the projection 140 of the sleeve 25' to move the sleeve 25' to the left as viewed in the latter figure withdrawing the plunger 29 from engagement with the crank arm 58 of the cam means 56 and to a position in which the end of the plunger 29 is free of lever 143 of the spring loaded stop member 142. Actuation of the foot treadle thus releases the releasable stop means formed by the sleeve 25' and plunger 29 and the stop member 142 to permit rotation of the plate and platen cylinder in the direction indicated in Figure 5 at the beginning of a single cycle of operation of the press. Upon positioning of the link 170 downwardly by pressing down on the treadle 162 it will be seen that at the end of the downward stroke of the link 170 that the flattened end portion 210 of bolt 175 is adapted to engage an adjustable screw 211 threaded in a laterally projecting ear 212 of the latch member 133 to move the latch member 133 downwardly against the force of leaf spring 137 from the position shown in Figures 8 and 9 to the position shown in Figures 10 and 11 in which position the clutch control rod 116 is released for movement axially to the right as viewed in Figure 6 to the position shown in Figure 7 so that clutch collar 106 engages the clutch for clutching gear 93 to the drive shaft 94. Thus in the tripped position of the manually operable trip means 160 the latch member 133 of latch means 132 is moved from the position shown in Figure 8 to the position shown in Figure 10 against the biasing force of leaf spring 137. With the latch member 133 in the position shown in the latter figure the notch 136 is disengaged from the side wall 6' above slot 135 and the spring 109 moves the clutch collar 106 to the right from the position shown in Figure 6 to the position shown in Figure 7. This movement of clutch collar 106 also shifts the shift fork 117 to the right moving the clutch control rod 116 axially in the latter direction and disposing the cam member 123 and lever 127 from the position shown in Figure 13 to the position shown in Figure 14. Now with the drive gear 93 clutched to drive shaft 94 the gears 92 and 90 are driven to rotate conjointly the cylinders 8 and 11. When the manual trip means is actuated to tripped position in the manner described, a second latch mechanism shown generally at 214 and comprising a lever 215 pivoted intermediate its ends at 216 on the side wall 6' is caused to be rotated slightly in a counterclockwise direction by a spring 218 to engage the notched end 219 thereof with the upper end of link 170 so that upon release of foot treadle 162 from its tripped position and the return thereof by spring 164 to its normal position the link 170 is maintained in tripped position maintaining the clutch for drive gear 93 engaged to drive the cylinders through a single cycle of operation. The slot and pin connection between foot treadle 162 and the lower end of link 170 permits return of the foot treadle to its normal position without affecting movement upwardly of link 170 to its non-tripped or normal position. As best shown in Figures 4, 5 and 15 the plate and platen cylinder 8 carries a pin 220, which as the

press approaches the end of a single cycle of operation or at the completion of a single revolution of cylinder 8, engages the end 223 of the latch lever 215 to move it from the position shown in full lines in Figure 15, or its latched position, to the dotted line position thereof of this figure to release the notched end 219 from the upper end of link 170 whereby spring 200 returns the latter link to its normal or uppermost position. Upon return movement of link 170 the several parts of the manually operable trip means 169 return to their normal or initial positions above described it being particularly noted that the spring 129 acting on lever 126 is effective for causing the cam member 123 to be biased axially outwardly from cam member 122 through the cam teeth 124 so that lever 126 acting against the adjacent thrust nut 128 shifts the clutch control rod to the left from the position of Figure 14 to the position of Figure 13 to disengage the clutch for drive gear 93 by movement of clutch collar 106 to the left from the position of Figure 7 to the position of Figure 6 by means of the shift fork 117. Upon the parts referred to assuming the position shown in Figure 13, the leaf spring causes latch arm to engage the portion of the side wall 6' above slot 135 to retain the clutch control rod 116 in position to disengage the clutch for gear 93 against the force of spring 109 normally tending to engage the clutch.

As previously referred to the other parts of the press last described such as the dampening and inking means 20 and 22, respectively, the gripper means 40, feed table 63, ejector cam 66, ejector wheel means 67, catcher 69, form roll cam 70, are all as described in connection with the press of Figures 1 and 2 in view of which it is believed a further description of such elements with respect of the press last described is not necessary. In the press of Figures 3 through 16 it will be observed that if desired the electric motor may be de-energized and the press manually driven through crank 23 and the slightly modified form of handle means 21' and alternate form of stop means 152 carried by the frame of the press in the same manner as the press of Figures 1 and 2 is operated.

It will be understood that if desired the presses above described may be modified for direct printing as previously referred to and as is known in this art by substituting a direct printing plate carrying segment for the impression segment 16 and by replacing the blanket cylinder 11 with an impression cylinder or removing the blanket 15 and substituting in its place a suitable impression member. Also, the plate carrying segment 17 preferably is removed and any other suitable segment substituted therefor. In the press as thus modified the dampening means 20 is removed or rendered inoperative and the inking means 22 preferably is disposed in the frame in a position in which it will be in juxtaposition of a portion of the main cylinder not in contact with the direct printing plate when the cylinders as thus modified are in position as illustrated in Figures 1 or 3.

While I have shown and described what I consider to be preferred embodiments of my invention it will be understood that various modifications and re-arrangements may be made therein without departing from the spirit and scope of my invention.

I claim:

1. In a printing press the combination of a pair of cylinders having intermeshing gear means and

forming a printing couple, a drive gear meshing with the gear means of one of said cylinders, a shaft adapted to be driven by a motor or the like, clutch means for clutching said drive gear to said shaft for conjointly rotating said pair of cylinders, releasable stop means associated with one of said cylinders for stopping said cylinders when the latter are disposed in predetermined relation with respect to each other, latch means associated with said clutch means for normally disengaging the same, normally closed gripper means rotatable with one of said cylinders, cam means associated with said releasable stop means for opening said gripper means when said cylinders are disposed in their said predetermined relation with respect to each other, manually operable trip means adapted to be disposed in tripped position for releasing said releasable stop means to disengage the same from said cam means for permitting said gripper means to close and release said cylinders for rotation, said manually operable trip means upon closing of said gripper means being thereafter adapted to disengage said latch mechanism whereby said clutch means is engaged to clutch said drive gear to said drive shaft to rotate said pair of cylinders, second latch means for said manually operable trip means for maintaining the latter in its tripped position, and means carried by said one cylinder for engaging said second latch means to release the same for return to its initial position upon the approach of said cylinders to their said predetermined position.

2. In a printing press having a pair of conjointly rotatable printing cylinders forming a printing couple, the combination of handle means including releasable means connected with one of said cylinders for rotating the same, stop means for said press adapted to be engaged by said releasable means of said handle means for preventing rotation of said cylinders when disposed in a predetermined relation with respect to each other, sheet gripper means carried by one of said cylinders, cam means mounted on said press for movement between operative and inoperative positions and in its operative position being adapted to engage with said sheet gripper means to open the same, spring means for said cam means for normally biasing the latter to its inoperative position, and said releasable means of said handle means in the said predetermined position of said cylinders engaging said cam means to dispose the latter to its operative position against the force of said spring means.

3. In a printing press having a stationary frame and a pair of printing cylinders mounted for rotation in said frame and forming a printing couple, the combination of normally closed sheet gripper means carried by one of said cylinders, handle means rigidly connected to one of said cylinders in non-rotative relation with respect thereto for rotating the latter, cam means pivotally mounted on said frame and having operative and inoperative positions, said cam means in its operative position being adapted to engage with said gripper means to open the latter, and manually operable means carried by said handle means for selective engagement with or disengagement from said cam means to effect thereby the selective disposal of the latter to its operative and inoperative positions.

4. In a printing press having a pair of printing cylinders mounted for rotation in said frame and forming a printing couple, the combination of normally closed sheet gripper means carried

by one of said cylinders, handle means rigidly connected to one of said cylinders in non-rotative relation with respect thereto for rotating the latter, cam means pivotally mounted on said frame for movement between operative and inoperative positions and in its operative position being adapted to engage with said gripper means to open the same, spring means for said cam means for normally biasing the latter to its inoperative position, and manually releasable means carried by said handle means for engaging said cam means to dispose the latter to its operative position against the force of said spring means.

5. In a printing press having a pair of printing cylinders forming a printing couple, the combination of sheet gripper means carried by one of said cylinders, handle means rigidly connected with said one cylinder in non-rotative relation with respect thereto for effecting rotation of the latter, cam means engageable with and disengageable from said gripper means in a predetermined position of said one cylinder and said handle means to open and close said gripper

means, and manually releasable means carried by said handle means for selectively effecting engagement or disengagement of said cam means with said gripper means to open and close the latter at said predetermined position of said one cylinder and said handle means.
